UNITED STATES PATENT OFFICE.

FRANCESCO LOMBARDI, OF NEW YORK, N. Y.

FOLDING RECEPTACLE.

1,127,046.

Specification of Letters Patent.

Patented Feb. 2, 1915.

Application filed May 3, 1913. Serial No. 765,289.

To all whom it may concern:

Be it known that I, FRANCESCO LOMBARDI, a subject of the King of Italy, residing at New York city, in the county of New York and State of New York, have invented new and useful Improvements in Folding Receptacles, of which the following is a specification.

The general object of the invention is to refine the construction of receptacles such as trunks, in point of adapting these receptacles to occupy a minimum of storage space when relieved of their contents and not in use. And to this end the invention resides in so connecting the sides and ends to the bottom of the receptacle and the top to one of the sides, as to admit of folding these several parts one upon the other, whereby, to contract the height of the receptacle when folded, to correspond approximately to the combined thicknesses of its several parts.

Other objects will appear and be better understood from that embodiment of my invention of which the following is a specification, reference being had to the accompanying drawings forming part hereof, in which:

Figure 1 is a perspective of the receptacle showing the several parts thereof folded. Fig. 2 is a vertical longitudinal section with the parts unfolded or in set-up position. Fig. 3 is a view similar to Fig. 2 but showing the parts folded. Fig. 4 is a vertical cross section on the line 4—4 of Fig. 2. Fig. 5 is a detail perspective of one part of the fastening device for connecting the top to the rear side wall. Fig. 6 is a view similar to Fig. 5 of the other part of said fastening device. Fig. 7 is a detail section of one of the fastening devices for detachably securing together the side and end walls. Fig. 8 is a view similar to Fig. 7 of a supplemental or modified form of fastener.

The receptacle comprises a bottom 5, end walls 6 and 7, side walls 8 and 9 and a top or cover 10. These several parts are so connected as to admit of their being folded one upon the other, from the position shown in Figs. 2 and 4 to those shown in Figs. 1 and 3. An ideal arrangement for effecting this result is shown in the drawings, but it must be understood that this is simply illustrative and the dispositions of the several parts may be varied and the same result obtained without departing from the spirit of the in-

vention. In carrying out my principle with the embodiment shown, hinges 11—11 are employed for connecting the end walls 6 and 7 to the bottom 5, and these hinges are disposed so as to admit of the said end walls folding inwardly upon the bottom from the vertical position shown in Fig. 2. Hinges 12—12 disposed so as to function similar to the hinges 11—11 are employed for connecting the side walls 8 and 9 to battens 13 and 14, which are suitably secured to the inner face of the bottom 5. These battens 13 and 14 are different from each other in point of height and so too, are the side walls 8 and 9, but the variation in height between the side walls is compensated for by connecting the shorter side wall to the higher batten, whereby to have the upper edges of the side walls coincident with each other and those of the end walls when all of said walls are unfolded, as shown in Figs. 2 and 4. By virtue of the variation in height between the battens 13 and 14 the side walls 8 and 9 are permitted to fold one upon the other, as shown in Fig. 3.

Straps 15—15 arranged on the inner face of the cover and disposed transversely thereof and located adjacent to the opposite ends of the cover, are terminally provided with opposed hooks 16—16 which take guideways 17—17 in the rear side wall 9. The guideways are formed by grooving the side wall in the direction of its width, such grooves being arranged in spaced pairs adjacent to the opposite ends of the side walls and partly overhung by the marginal portions of straps, one of which is shown in enlarged detail in Fig. 6 and indicated by 18. The presence of these straps prevent accidental disengagement of the cover from the side wall 9 and the curved upper ends 19 of the straps coöperate with the hooks 16—16 to function as hinges when the cover is raised and lowered and the parts in set up position, as shown in Figs. 2 and 4.

Casings 20 carrying spring-pressed bolts 21 are attached to the end walls 6 and 7 and disposed so as to have the engaging ends of the bolts normally projecting beyond the lateral edges of the ends. At points in the side walls 8 and 9 alining with the engaging ends of the bolts when the parts are in set up position, sockets 22 are formed, into which the engaging ends of the bolts pass under the action of their springs 23 upon the turning of the end walls into set-up po-

sitions between the previously adjusted side walls.

A fastening device in the form of a frame 24 and spring clips 25 may be employed to supplement the bolt fasteners or used in lieu thereof, as desired. The presence of the frame 24 when engaged by the clips 25 as shown in Figs. 2 and 4, reinforces the side walls and also the end walls so as to more effectively withstand pressure from without.

Corner reinforcing devices in the form of angle straps 26 are secured to certain of the walls and arranged so as to surround the corner joints when the walls are in set up position. An additional reinforcement against collapsing of the walls under exterior pressure, is had by grooving the upper edges of the end walls and forming ribs 27 on the inner face of the cover to enter the grooves when the cover is closed.

A pocket for receiving the folded side and end walls and the top is had by attaching strips 28 of suitable widths to the edges of the bottom 5 and attaching a keeper 29 to one of these strips so as to coat with the hasp 30 of the cover, admits of locking the several parts in their folded positions.

The parts of the receptacle are folded by raising the cover to a vertical position and allowing it to descend over the outer face of the rear side wall 9, then disengaging the fastening devices from the side walls in or-

der to allow the folding inwardly upon the bottom, of the end walls. This done, the front side wall is folded over the end walls, after which the rear side wall carrying the top may be folded over the front side wall, in which position the top will occupy the position shown in Fig. 1 and the several parts folded within the space afforded by the pocket.

If desired, suitable locks 31—31 may be attached to the keepers 29 as shown in Fig. 1. In setting up the parts of the receptacle, the foregoing operation of the several parts is reversed.

What is claimed as new is:

In a folding receptacle a side wall, straps disposed transversely upon said wall, said side wall having grooves over which the edge portions of said straps extend, a top adapted to move along the outer surface of said wall, hooks carried by the top and engageable under the edge portions of said straps and received within the grooves and means located at the ends of the straps for limiting the movement of the hooks and top.

In testimony whereof I affix my signature in presence of two witnesses.

FRANCESCO LOMBARDI.
